UNITED STATES PATENT OFFICE.

GEORGE SAMUEL THOMSON, OF DUNEDIN, NEW ZEALAND.

AUTOMATIC COLLAPSING AND REERECTING TROLLEY-POLE.

No. 895.314.

Specification of Letters Patent.

Patented Aug. 4, 1908.

Application filed November 29, 1907. Serial No. 404,455.

To all whom it may concern:

Be it known that I, **GEORGE SAMUEL THOMSON**, a public accountant, a subject of the King of Great Britain, and resident of the city of Dunedin, in the British Dominion of New Zealand, and whose post-office address is Dunedin, have invented new and useful Automatic Collapsing and Reerecting Trolley-Poles, of which the following is a specification.

10 specification.
The object of this invention is to cause the
upper portion of an ordinary trolley pole,
used in electric vehicles, to collapse, so that
the whole becomes lower than any of the
15 overhead gear or cables, if the usual trolley
wheel happens to leave the said electric
cable, which action causes the pole to be-
come upright when it is liable to cause dam-
age to said overhead gear. For this purpose
20 I cut an ordinary pole sufficiently low to be
lower than the cable when upright, and make
a flush joint strengthening the pole by a
long sheath which keeps the pole rigid when
working, and helps in reerection. The whole
25 is arranged to collapse when the pole be-
comes too upright but to be rigid at other
times.

Referring to the accompanying drawing:—
Figure 1 is a side elevation of an ordinary
trolley pole with my invented gear in position,
the whole at the usual working angle
and Fig. 2 is an enlarged detail of the joint if
collapsed.

A is the lower and A' the upper part of the
35 hinged pole.

A^2 is the usual socket and cantaliver on the car.

B is the 'joint' and B¹ the strengthening sheath.

40 B^2 is a rest or buffer to catch the pole as it falls.

C is a sliding ferrule sliding over the point of B¹ keeping the pole normally rigid, it is kept from falling by a light spring and adjustable ferrule C¹.

D is a double rod with slots which removes C from B¹ when the pole becomes too upright but otherwise allows it complete freedom. This is adjustable as to tripping angle by the holes at D¹ and is bent over to the other side of the pole at D².

E is the reerecting cord preferably the useless end of the usual cord E'. In reerecting when E is pulled the pole A' is brought in line with A and then the continued action 55 lands the whole till C rises over the point of

B¹. Then either cord E or E¹ may be used to replace the wheel under the cable in the usual way.

E^2 is a rubber block fastened at a suitable point on the reerecting cord E and E^3 a directing pulley, the block being arranged to strike the pulley E^3 as a buffer as the upper pole section approaches a horizontal position and thereby lessens the jar of the falling pole. 65

In this invention any suitable materials or sizes may be adopted.

Having described my invention what I claim and desire to secure by a patent of the United States of America, is:—

1. A movably mounted trolley pole comprising pivotally connected upper and lower sections, a catch for retaining the said sections in rigid relation, and a tripping device embodying a link having one end mounted on a fixed pivot separate from the pole and having its opposite end arranged to co-operate with said catch and capable of a limited relative movement to release the sections when the pole assumes a predetermined position. 75 80

2. A swinging trolley pole comprising pivotally connected sections, a catch slideable longitudinally of the pole for retaining said sections in rigid relation, and a tripping device mounted separately from the pole embodying a link connected at one end to a fixed pivot and co-operating at its opposite end with said catch to move the latter longitudinally of the pole and permit relative pivotal movement of the sections when the pole assumes a predetermined position. 85 90

3. A pivotally mounted trolley pole comprising upper and lower sections pivotally connected, a rigid portion on one section extending beyond the pivotal connection and overlapping the other section, a catch embodying a sleeve surrounding and slideable on one section and arranged to overlap the said rigid portion of the other pole to lock the sections in rigid relation, and a device controlled by the swinging movements of the pole for sliding the catch to unlock the sections. 95 100

4. A trolley pole mounted for swinging movement and comprising pivotally connected upper and lower sections, one of the sections having a semi-tubular extension rigid thereon and overlapping the other section, a catch embodying a sleeve surrounding one section and slidably over the extension of the other section to lock the sections in rigid relation, and a device controlled by the

swinging movements of the pole for sliding the sleeve to unlock the sections.

5. A trolley pole mounted for swinging movement and comprising upper and lower pivotally connected sections, a catch for retaining said sections in rigid relation, and a tripping device mounted separately from the pole and having a slidable connection for permitting a limited movement between it and 10 said catch, the tripping device being controlled by the swinging movements of the pole for releasing the catch when the pole assumes a predetermined angular position.

15. A trolley pole mounted for swinging movement and comprising pivotally connected upper and lower sections, a catch slidable longitudinally of the pole for locking the sections in rigid relation, and a device mounted on a relatively fixed pivot and having its opposite end attached to and capable 20 of a limited movement relatively to said catch to move the latter longitudinally of the pole as the latter alters its angular position.

25. The combination of a trolley stand, a pole mounted for swinging movement thereon and comprising pivotally connected upper and lower sections, a catch for locking the sections in rigid relation, a tripping device embodying a link having one end pivoted on 30 the stand and its other end slidingly coöper-

ating with the catch to control its operation during the swinging movement of the pole, an extension being provided on the upper section which overlaps a portion of the lower section and coöperates with said catch, a pulley secured to the stand, and a reerecting cord attached to the lower end of said extension and coöperating with said pulley. 35

8. The combination with a trolley stand, a pole mounted for swinging movement thereon comprising pivotally connected upper and lower sections, the upper section having a rigid extension thereon overlapping the lower section, a sleeve movable longitudinally on the lower section and arranged to 40 coöperate with said extension to lock the sections in rigid relation, a spring normally acting on said sleeve to move it into locking position, and a tripping device embodying a rod pivoted at its lower end to said stand and 45 having a pin and slot connection with said sleeve for controlling the latter according to the angular movements of the pole. 50

In testimony whereof I have hereunto set my hand in the presence of two witnesses. 55

GEORGE SAMUEL THOMSON.
